MODULATION SYSTEM

John Evans, Palmyra, N. J., assignor to Radio Corporation of America, a corporation of Delaware

Application May 27, 1941, Serial No. 395,329

6 Claims. (Cl. 179—171.5)

This invention relates to a modulation system and particularly to a system of phase or frequency modulating a radio frequency carrier and for stabilizing the mid-frequency of the carrier.

An amplitude modulation system may be defined as one in which the amplitude of the carrier is varied as a function of the signal so that the envelope of the carrier represents the signal. In phase modulation, if a signal of constant amplitude and variable frequency is applied to a carrier, sidebands of constant amplitude are established for all signal frequencies. If a similar signal of constant amplitude and variable frequency is applied to frequency modulate a carrier, the amplitude of the resulting sidebands will be different for different audio frequency. Inasmuch as the output from a frequency modulated transmitter may be converted, by means of a signal modifying network, into a phase modulated wave, or a phase modulated transmitter into a frequency modulated wave, no distinction will be made in describing this invention which may be applied to frequency or phase modulating devices. Therefore, it should be understood that the terms "phase modulation" and "frequency modulation" are used synonymously.

In a copending application entitled Phase modulated transmitters, Serial No. 390,053, filed April 24, 1941, by John L. Barnes and assigned to the same assignee as the instant application, a frequency or phase modulation system is described. While the mid-frequency is stabilized, a substantial number of filter sections are required to obtain the desired phase shift. The instant application discloses a system or method for obtaining the desired phase shift in a transmission line, which may readily be made of the required length by using high frequency and hence short wave lengths. If currents of high frequency are applied to a line, of say $n\lambda$ length where n is a constant and λ is the wave length of the applied current, the phase shift will be multiplied in the line by n . It is a decided improvement, especially from the practical standpoint, to use a line in place of a multisection filter. The line is not only cheaper but any required length may be coiled into a small space.

The invention will be described by referring to the accompanying drawing in which Figure 1 is a schematic block diagram of one embodiment of the invention; and Figure 2 is a graph illustrating the phase shift of the invention.

Referring to Fig. 1, a crystal oscillator 1 or other stabilized source of high frequency oscilla-

tions is connected through a frequency multiplier 3 to a transmission line 5. The output of the transmission line is connected to a beat frequency detector 7. The output of the beat frequency detector is applied to a transmitter 9 which is connected to an antenna 11 or other load circuit. The signal is applied, through a pre-emphasis network 13 is desired, to a reactance modulator 15. The reactance modulator 15 is connected to a frequency modulated, and preferably stabilized, oscillator 17. The output of the frequency modulated oscillator is applied to the transmission line 5.

The operation of the circuit is essentially as follows: The currents from the crystal oscillator are multiplied to obtain a stabilized source of current of a frequency of 200 megacycles, by way of example. These currents are shifted in phase by the transmission line 5 but the phase shift is constant at the output of the line because the frequency of the applied current is constant. In the absence of modulation, currents of say 150 megacycles, from the line stabilized oscillator will also be subjected to a constant phase shift in the transmission line. The currents from the two sources 3 and 17 are combined in the beat detector to produce a beat frequency of 50 megacycles which is applied through the transmitter to the load circuit. Since both sources are stabilized the output currents will be stabilized at the mid or unmodulated frequency F_0 .

If the signals are applied the reactance modulator 15 will react on the line stabilized oscillator to change its frequency. The new frequency, say $F+$ will be shifted in phase as indicated in Fig. 2. If the line 5 is many times longer than the wave length the phase will be shifted by many radians. For example, if the reactance tube shifts the phase by one radian and the phase shifting transmission line is 100 wave lengths long, the phase will be shifted 100 radians. In a like manner the phase may be shifted for an increasing frequency $F-$ as shown in Fig. 2. Thus the phase is advanced or retarded with respect to the phase of the mid-frequency and the currents applied to the load circuit are phase or frequency modulated.

While the two frequencies have been selected as 150 and 200 megacycles, it should be understood that these were chosen by way of exemplification and not limitation. Furthermore, the transmitter may include a frequency multiplier to multiply the output frequency if a greater frequency shift than may be conveniently obtained by the transmission line 5 is required. Inas-

much as the oscillators, reactance modulator, frequency multiplier, transmission line, beat frequency oscillator, and the transmitter are all elements well known to those skilled in the art, detailed wiring diagrams are unnecessary to an understanding of the invention.

I claim as my invention:

1. A modulation system including a source of frequency stabilized oscillations, a source of phase modulated oscillations, a transmission line for shifting the phase of said modulated oscillations, means for applying oscillations from said two sources to the input of said line, means connected to said line for combining the oscillations applied thereto to obtain currents having a frequency equal to the beat frequency of said applied oscillations, and means for applying said beat frequency currents to a load circuit.

2. A modulation system including a source of frequency stabilized oscillations, means connected to said source for multiplying said frequency, a source of phase modulated oscillations, a transmission line of a length equal to $n\lambda$ where n equals a constant and λ equals the wave length of said phase modulated oscillations, means for applying oscillations from said source and said multiplier means to said line, a beat frequency detector effectively connected to said line for deriving a current corresponding to the beat frequency of the applied currents, and means for applying said beat frequency currents to a load circuit.

3. A modulation system including a source of frequency stabilized oscillations, a source of phase modulated oscillations, a transmission line of a length corresponding to $n\lambda$, where n is a constant and λ is the wave length of the modulated oscillations, means for applying oscillations from said sources to the input of said line, means associated with the output of said line for combining the line output currents to obtain a current corresponding to the beat frequency of the applied oscillations, and means for applying said beat frequency current to a load circuit.

4. A modulation system including a source of frequency stabilized oscillations, a source of phase modulated oscillations, a transmission line of a length corresponding to $n\lambda$, where n is a constant and λ is the wave length of the modulated oscillations, means for applying oscillations from said sources to the input of said line, means associated with the output of said line for combining the line output currents to obtain a current corresponding to the difference in frequency of the applied oscillations, and means for applying said difference frequency current to a load circuit.

5. A modulation system including a source of frequency stabilized oscillations, a source of phase modulated oscillations, a transmission line for shifting the phase of said modulated oscillations, means for applying oscillations from said two sources to the input of said line, means connected to said line for combining the oscillations applied thereto to obtain currents having a frequency equal to the difference in frequency of said applied oscillations, and means for applying said difference frequency currents to a load circuit.

6. A modulation system including a source of frequency stabilized currents, means connected to said source for multiplying said frequency, a source of phase modulated currents, a transmission line connected to said multiplying means for shifting the phase of said frequency multiplied currents a constant amount, means for applying said phase shifted currents to said transmission line for multiplying the amount of said phase shift, means effectively connected to said transmission line for combining the currents applied thereto so that the resulting current has a frequency equal to the beat frequency of the applied currents and a phase shift which varies as the phase shift of said phase modulated currents multiplied by the phase shift occurring in said line.

JOHN EVANS.
